(57) **CLAIM**

The ornamental design for a cat doorknob cover, as shown and described.

DESCRIPTION

FIG. 1 is a top right perspective view of the cat doorknob cover of my design;

FIG. 2 is a top right rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof; and,

FIG. 9 is a top left perspective exploded view thereof in combination with a doorknob shown in broken lines.

The broken lines shown represent portions of the cat doorknob cover and environmental subject matter that form no part of the claimed design.
